DATA ENTRY KEYBOARD CONSOLE

Frederick E. Barrett, New York, N.Y. (a/ Comspace Corp., 2372 Linden Blvd., Brooklyn, N.Y. 11208)

Filed July 20, 1966, Ser. No. 3,138

Term of patent 14 years

(Cl. D26—5)

FIG. 1 is a front perspective view of a data entry keyboard console embodying my new design;

FIG. 2 is a front elevational view thereof;

FIG. 3 is an elevational view taken from one side thereof; and

FIG. 4 is a fragmentary rear elevational view, the broken away portion being omitted for convenience of illustration.

I claim:

The ornamental design for the data entry keyboard console, as shown.
